INTERMITTENT STEAM-BOILER FEED

Application filed August 29, 1928. Serial No. 302,861.

My invention relates to feeding devices for steam boilers and more particularly to devices for feeding water intermittently to boilers; and the object is to provide simple devices which will operate automatically for feeding water intermittently to boilers when once started and to provide an economical method of operating steam boilers to maintain an adequate supply of steam for the purposes required. Reference is had to the accompanying drawings which form a part of this application.

Other objects and advantages will be fully explained in the following description and the invention will be more particularly pointed out in the claims.

Fig. 1 is a diagrammatic view of the invention, partly in section.

Fig. 2 is a longitudinal section of the movable sleeve used in the operation of the improved feed.

Fig. 3 is a side elevation of the piston.

Similar characters of reference are used to indicate the same parts throughout the several views.

This invention includes a casing 1 in which a piston 3 moves. A reducer 2 is screwed on one end. The casing 1 is connected to a water supply source by a pipe 4 which is provided with a check valve 5. A T-pipe 6 is connected to the reducer 2 and to the pipe 4 through the check valve 5 casing. A movable sleeve 7 is mounted in the casing 1 and the piston 3 is mounted in the sleeve 7. A pipe 8 leads to a boiler and is connected to the T-pipe 6 through a check valve 9. A heating coil 10 is provided. The casing 1 has a boss 11 and the coil 10 has a valve 12 connected thereto and the valve 12 is connected to the coil 10. The coil 10 is also connected to the casing 1 which has an L-extension 13 to which the coil 10 is connected. The casing 1 has an exhaust opening 14.

The devices herein described are for use where there is a water pressure. The piston 3 and the sleeve 7 are automatically moved by the pressure of the water. The coil 10 is a heating coil and may be located in the furnace. When water is let in the casing 1 from the pipe 4, the piston 3, if not

already below the coil connection 11, will be pressed by the water below the connection 11 so that water will enter the coil 10 to be heated and converted into steam. When the water is sufficiently heated, the water and steam will escape from the coil through the opening 13 into the sleeve 7 below the piston 3. If the water is sufficiently heated, it will be heated and converted into steam and overcome the pressure of water from the pipe and force the piston 3 above the discharge opening 11 and so stop the flow of water into coil 10. The sleeve 7 has a discharge opening 15. When the piston 3 passes above the opening 15, hot water and steam will escape through the opening 15 and the groove 16 in the casing 7 and then out through the pipe 8 to the boiler. As soon as the force of the hot water and steam become less than the water pressure coming through pipe 4, the cold water will again press the piston 3 below the discharge opening and pass through the opening 11 to be heated and converted into steam in the coil 10. The operation will then be as above described. Such operations will go on continually. The sleeve 7 normally closes the exhaust 14 by means of the valve 17, but if there is excess of hot water and steam pressure, the piston will be pressed against the upper part of the sleeve 7 and lift the sleeve 7 upwardly so that the excess pressure will escape as soon as the sleeve 7 comes into communication with the exhaust opening 14. Any pressure exceeding 30 pounds will operate the feeding devices.

The lower end of the sleeve 7 constitutes a valve 17 for the purpose of bleeding the expansion coil 10 after the sleeve 7 passes to the top of casing 1 for reducing the pressure in coil 10 to atmospheric pressure. Immediately cold water will enter and force the piston and sleeve down, and cold water will again enter the casing 1 and sleeve 7.

What I claim, is,—

1. An intermittent steam boiler feed comprising a casing, a sleeve movable longitudinally therein and having an intake opening for receiving a supply of water, a T-pipe connected to said casing for supplying water to said sleeve and for discharging hot water

therefrom, a heating coil connected to said casing and adapted to communicate with said sleeve for receiving water therefrom and connected to said casing below said sleeve for discharging hot water into said casing and sleeve, and a piston movable in said sleeve by incoming water supply until the piston opens communication with said coil and movable by hot water and steam from said coil when the pressure from said coil becomes greater than the pressure of incoming cold water from the supply source to cut off the cold water supply and to discharge hot water and steam from said sleeve and casing to a boiler.

2. An intermittent steam boiler feed comprising a casing, a sleeve movable longitudinally therein and having communication with a supply source of water and having communication with a boiler through said casing, a heating coil having connection with said casing and communicating with said sleeve for receiving a supply of water to be heated and a second connection with said casing for discharging hot water and steam into said casing and sleeve, and a piston movable longitudinally in said sleeve by a water supply coming into said sleeve until the piston passes said heating coil connection and movable by hot water and steam from said coil when the hot water pressure becomes greater than the cold water supply for stopping the supply and for discharging hot water from said sleeve and casing to a boiler.

3. An intermittent steam boiler feed comprising a casing having communication with a supply source of water and communication with a boiler and having heating coil connections and an exhaust, a sleeve movable longitudinally in said casing and having an intake opening for receiving a supply of cold water and having a discharge for cold water to a heating coil and a discharge for hot water to said boiler and an intake for hot water from said heating coil, a heating coil having cold and hot water connections with said casing and sleeve, and a piston movable longitudinally in said sleeve by cold water supply until the piston passes the cold water connection with said heating coil and movable by hot water pressure from said coil when said pressure becomes greater than the pressure of the cold water supply to stop the cold water supply and to discharge hot water through said sleeve and casing to a boiler, and said sleeve serving as a valve to close said exhaust during normal operations and said piston being adapted to move said sleeve to open said exhaust in case of excessive pressure from said heating coil.

In testimony whereof, I set my hand, this 27th day of June, 1928.

ADRA M. HUBBARD.
